UNITED STATES PATENT OFFICE.

HARRY HELLER, OF NEW YORK, N. Y.

PRESSER FOOT.

Application filed December 17, 1921. Serial No. 523,147.

To all whom it may concern:

Be it known that I, HARRY HELLER, a citizen of the United States, and a resident of the borough of Manhattan, in the county of New York and State of New York, have invented certain new and useful Improvements in Presser Feet, of which the following is a specification.

This invention relates to improvements 10 in presser feet.

A purpose of this invention is to provide a presser foot for sewing machines, interchangeable with those of common construction, whereby the edge or hem of a textile 15 fabric may be guided in producing a parallel stitched seam, the presser foot being also operative as a guide for raised insertion upon the margin of a body fabric.

A further purpose is in the provision of 20 means tending to aid in the illumination of the parts to be sewn directly in front of the needle.

These and like advantageous objects, becoming apparent as the description progresses, are attained by the novel arrangement, construction and combination of parts 25 hereinafter described and shown in the accompanying drawing, forming an essential part of this disclosure, and in which:—

30 Figure 1 is a perspective view of a presser foot made in accordance with the invention, looking from the lower right hand side thereof.

Figure 2 is a partial side elevational, 35 partial longitudinal sectional view of the same, the section being taken approximately on line 2—2 of Figure 1.

Figure 3 is a transverse sectional view taken on line 3—3 of Figure 2.

40 In this drawing the numeral 5 designates the front element of the presser foot shank, the same being slightly increased in thickness from its upper edge downward and having along its upper portion an angular 45 rearward extension 6 formed with a plate 7 parallel to the front plate 5, these elements constituting an open box like frame suited to receive the presser foot bar (not shown).

It is preferred to form a slot 8 in the 50 tension plate 6 to receive the shank of a binding screw by which the presser foot is engaged to the bar, the head of the screw being received in a center bore 9, the axis of which is co-incident with the curved bottom 55 of the slot 8.

Extending forward at a right angle from the thicker portion of the shank is a slightly wider plate 10 containing a drilled opening 11 through which the sewing machine needle passes when in operation, and entering the opening is a slot 12 dividing the plate into branches or forks 13 and 14 of unlike width and conformation.

The fork 13 extends further to the front and is curved upwardly as at 15 and terminates in a rounded edge 16, the other fork 14 is relatively shorter and formed with an obtuse end 18 terminating in the edge 19.

A channelled pocket or recess 20 is provided in the fork 14, the same extending 70 from the rear or heel portion toward the front, terminating in an undercut portion 21 and open at the bottom.

A guide bar 22 is pivoted in the recess 20 by a pin 23 at any preferred point at 75 the rear, this bar having a curved front portion 24 adapted to engage within the undercut portion of the recess, as shown in Figures 1 and 2.

A hole 25 is drilled into the upper side 80 of the guide bar to receive a spring 26 abutting the interior of the recess and serving to press the guide bar downwardly and outwardly into operative position.

Obviously the pivot pin may be arranged 85 in a different location and the type of spring used is optional.

In order to admit a ray of light upon the needle or path of stitching, an elongated opening 27 is formed through the shank 90 plate 5, the same acting as a window for the purpose.

In operation, the presser foot is applied to the machine in the usual manner so that when lowered contact is made with the material to be stitched.

If the edge of the fabric, or a hem previously formed on it be presented adjacent the side of the spring pressed guide it is apparent that the same may be accurately 100 guided, as will also be an insertion of narrow fabric, as braid, its edge being guided with the edge of the body fabric below.

While a certain preferred embodiment of the device has been shown and described, it 105 will be understood that changes may be made in proportion, and detail without departing from the scope of the invention as defined in the appended claims.

Having thus described my invention, what 110

I claim as new and desire to secure by Letters Patent, is:—

1. A presser foot comprising a shank suited for attachment to a presser foot bar, said shank having a relatively wide front portion extending below the bar and containing a wide elongated opening permitting the passage of light, and a forked plate extending at an angle forwardly from said shank adapted to contact with material entered therebelow.
2. A presser foot comprising a shank, a forked pressure plate integral therewith, one of said forks containing a longitudinal pocket in its lower side, a guide bar suited to fit flush within the pocket, said bar being pivoted at one end therewithin, and resilient means in the pocket adapted to normally project said bar limitedly outward.
3. A presser foot comprising an attaching shank, a forwardly extending presser plate formed therewith, having forked ele-

ments, the shorter of said elements being longitudinally pocketed on its under side, a pivoted lever arm disposable in the mentioned pocket, and means for normally projecting said arm to extend in the manner of a guide rib parallel and below said fork plate.

4. A presser foot comprising an attaching shank, a forked presser plate at a right angle in advance thereof, one of said forks being relatively narrow with respect to the other, said narrow fork containing a recess extending upward from the bottom from one end nearly to the other, a guide bar pivoted at its rear end in said recess, its front end engaging with the undercut front end of the recess, and a spring adapted to normally maintain said bar extended below said fork.

Signed at New York, in the county of New York and State of New York this 14th day of December, A. D. 1921.

HARRY HELLER.
